US0D1044232S

(12) **United States Design Patent** (10) **Patent No.:** **US D1,044,232 S**
(45) **Date of Patent:** **** Oct. 1, 2024**

(54) **SHOE**

(71) Applicant: **PUMA SE**, Herzogenaurach (DE)

(72) Inventors: **Andreas Siegismund**, Rückersdorf (DE); **Romain Girard**, Lauf an der Pegnitz (DE)

(73) Assignee: **PUMA SE**, Herzogenaurach (DE)

(***) Term: **15 Years**

(21) Appl. No.: **29/891,899**

(22) Filed: **May 11, 2023**

Related U.S. Application Data

(63) Continuation of application No. 29/760,391, filed on Dec. 1, 2020, now Pat. No. Des. 1,003,018.

(51) **LOC (14) Cl.** **02-04**

(52) **U.S. Cl.**

USPC **D2/947**

(58) **Field of Classification Search**

USPC ..... D2/896, 900, 902, 904, 906–908, D2/916–924, 925–945, 947–960, 969–979 CPC A43B 1/00; A43B 1/02; A43B 1/04; A43B 3/00; A43B 3/02; A43B 3/06; A43B 3/10; A43B 3/12; A43B 3/14; A43B 5/00; A43B 5/001; A43B 5/008; A43B 5/10; A43B 5/12; A43B 23/00; A43B 23/02; A43B 23/04

(57) **CLAIM**

The ornamental design for a shoe, as shown and described.

DESCRIPTION

FIG. 1 is a top, right, front perspective view of an ornamental design for a shoe;

FIG. 2 is a right side elevational view of the shoe of FIG. 1; FIG. 3 is a left side elevational view of the shoe of FIG. 1; and,

FIG. 4 is a rear elevational view of the shoe of FIG. 1. The dash-dash-dash broken lines are included for the purpose of illustrating portions of the shoe that form no part of the claimed design.

1 Claim, 4 Drawing Sheets
